[57] CLAIM

The ornamental design for a surface treatment for a chair, as shown and described.

DESCRIPTION

FIG. 1 is a front view of the surface treatment for a chair. FIG. 2 is a side view of the surface treatment for a chair of FIG. 1, the other side of the surface of a chair being the mirror image of this view; and,

FIG. 3 is a top plan view of the surface treatment for a chair of FIG. 1.

The portions of the chair shown in broken lines have been shown for illustration purposes only and do not form part of the design.
